L. H. Osgood,

UNITED STATES PATENT OFFICE.

GEORGE LOCKHART, OF NEW YORK, N. Y.

CURTAIN-POLE ATTACHMENT.

SPECIFICATION forming part of Letters Patent No. 366,330, dated July 12, 1887.

Application filed July 26, 1886. Serial No. 209,047. (No model.)

To all whom it may concern:

Be it known that I, GEORGE LOCKHART, of New York city, county of New York and State of New York, have invented certain new and useful Improvements in Curtain-Pole Attachments, of which the following is a full, clear, and exact description, reference being had to the accompanying drawings, and to the letters of reference marked thereon.

10 My invention has relation to the attachments or appliances for curtain-poles, cornices, and other devices or media upon which curtains are sustained, which attachments or appliances are employed in shifting or moving the curtains or the curtain-sustaining rings back and forth upon the support.

15 The objects of my improvements are to produce simple, cheap, and durable appliances, which may be readily connected with any curtain pole or rod, or cornice, or other support, which will be easy to operate, not liable to get out of order or to become disarranged, and which will obviate scratching of the rings against the surface of the pole or rod and undue wearing of the operating-cord. To accomplish these objects my improvements involve certain novel and useful peculiarities of construction and relative arrangements or combinations of parts, all of which will be herein 25 first fully described and then pointed out in the claims.

30 In the accompanying drawings forming part of this specification, Figure 1 is a side elevation, and Fig. 2 a top or plan view, of a curtain-pole having my improvements applied thereon, the rings being shown in position to hold the curtains drawn back. Fig. 3 is a side elevation of the same pole, showing the curtain-supporting rings at intervals along the 35 length of the pole, as when the curtains are drawn together. Fig. 4 is an elevation, on a scale enlarged beyond that of previous figures, of the single pulley and its stem detached from its support, and Fig. 5 is a similar view showing the double pulley. Fig. 6 is an elevation 40 showing the pulleys applied to the inner face of an ordinary cornice; and Figs. 7 and 8 are sectional elevations showing the two pulleys in position, as in Fig. 6, all indicating also 45 how the pulleys may be applied upon any supporting object.

In all the figures like letters of reference

wherever they occur indicate corresponding parts.

It has not been deemed necessary to represent the curtains, inasmuch as they are attached to the curtain-rings in the usual manner and move with the rings.

55 A represents a curtain-pole upon which the curtain-sustaining rings *a a a* are mounted and arranged to slide back and forth, the curtains being usually attached to small screw-eyes, as *a' a'*, located in the rings, especially when the rings are made of wood.

50 B is the operating-cord by which the rings, and thus the curtain depending therefrom, are moved back and forth upon the pole. Near one end of the pole is a double-pulley block, C, containing a pair of grooved sheaves to accommodate a cord. This block is connected 70 with the pole by a hollow shaft or stem, b, large enough to permit the two sections of cord to run therein easily, and the block is mounted on the top of the pole and held in place by the hollow stem *b*, which passes through the material of the pole, the stem being threaded into the block and having a bead or rim, *b'*, which bears against the under side of the pole. Instead of threading this stem into the block the lower end might be threaded and receive a 75 nut, which would bear against the pole and clamp the block in place; but the construction shown in the drawings is deemed preferable, because it gives a better and closer finish.

80 The pulleys or sheaves in the double block 85 C are mounted upon horizontal axes, so as to better guide the sections of the cord into the hollow stem, and I prefer to place a partition between the two pulleys or sheaves, as shown at *c*, to aid in keeping the cord in place. At 90 or near the other end of the pole is a single-pulley block, D, the pulley therein being preferably mounted upon a vertical axis and the block sustained by a solid stem, *d*, passing down through the pole and held by a nut on 95 the projecting end.

90 The cord is carried up through the hollow stem *b*, over one of the pulleys in block C, along the top of the pole, and between it and the rings made to engage with one of the middle 100 rings, thence in the same manner between the pole and the remaining rings and back to one of the middle rings, to which it is attached, then between the pole and remaining rings, over

the second pulley in block C, and down through the hollow stem *b*. Being thus arranged, by pulling down on one end of the cord the rings will be drawn together at the ends of the pole, as in Figs. 1 and 2, and by pulling down on the other end of the cord the rings will (when the curtains are attached) be distributed along the pole, as in Fig. 3. While the rings are moving the pole is protected from wear by the intervening cord, which raises them off or away from the pole and makes it easier to slide the curtains, which are sometimes quite heavy, and prevents the inclination or wedging of the rings to a great extent. The cord and pulleys being above the pole are not so much exposed to view as when placed below it, and the cord is prevented from sagging, and thereby detracting from the appearance of the curtain fixtures.

Instead of connecting the cord with the ring at the center I generally prefer to connect it with those next adjacent, by which a better movement of the rings is secured; but this is immaterial.

The connection between the cord and rings is generally made by a simple turn of the cord about the rings, as shown, though any convenient means for connection might be employed instead.

I am aware that cords have heretofore been run along on the under side of the pole, and also that a cord has been run in a groove cut in the top of the pole, neither form, however, having the pulleys as herein described. In the first form the cord seriously interferes with the movement of the rings, causing them to drag on the top and sides, and the second form requires a groove to be cut out of the pole and the pulley to be located on one side, and is not applicable except upon poles of particular construction. My improved appliances are applicable alike to wooden or metallic or covered poles, (wooden poles covered with metal,) whatever their form or construction, and require no alteration in the pole save the piercing of two small holes for the stems of the pulley-blocks, and may be quickly applied upon old or new poles without the aid of special tools.

At Figs. 6, 7, and 8 the improved appliances are shown as mounted upon the inner face of an ordinary window-cornice. E represents the body of the cornice, usually having projecting end pieces, as at E' E'. The single-pulley block is sustained in ordinary screw-eyes *e e*, entering the material of the cornice, and the double-pulley block sustained in like manner by screw-eyes *ff*. A suitable rod, as A', serves to guide the curtain-rings,

(in this case usually smaller than those employed on the pole,) and the rod is sustained upon the cornice by screw-eyes, as *g g*, or by other suitable means. The cord is applied as before and the curtain is moved as before. The pulley-blocks are rigidly held in proper place by screwing the stem or nut so as to secure a firm bearing against the screw-eyes. In like manner the blocks may be mounted upon the window-casing or upon any object of support. They may be easily removed when desired, and generally they will be found to admirably answer the purpose or objects of the invention, as previously set forth.

Having now fully described my invention, what I claim as new, and desire to secure by Letters Patent, is—

1. The combination, with a curtain-pole, of the double-pulley block for the operating-cord, the same being provided with a hollow stem passing through the body of the pole and receiving the cord, substantially as shown and described.

2. In combination with the double-pulley block, the hollow stem constructed and arranged substantially as described, and provided with a bead or rim at bottom to bear against the under side of its support and securely hold the block in place, for the purposes and objects set forth.

3. In attachments for curtain-poles, &c., the double and single pulley blocks for the operating-cord, said blocks being provided with shanks or stems, one of which is made hollow or tubular, each arranged, as explained, to secure the blocks firmly in place upon the support, and each projecting entirely through the support, and combined with each other and with the support, substantially as shown and described.

4. The combination of the pole, the curtain-rings movable thereon, the operating-cord located between the rings and the pole and preventing contact of the rings and pole, and the double and single pulley blocks mounted upon the top of the pole, and each provided with shanks projecting entirely through the pole, and with a nut or rim bearing against the under side of the pole, the shank connected with the double block being made hollow or tubular, substantially as shown, and for the purposes set forth.

In testimony that I claim the foregoing I have hereunto set my hand in the presence of two witnesses.

GEORGE LOCKHART.

Witnesses:

JOHN BUCKLIN,
WORTH OSGOOD.
